HOLDER FOR FOOD BOWL FOR PETS

Tony Robert, 5701 Southwest Freeway,
Houston, Tex. 77027

Filed Feb. 13, 1968, Ser. No. 10,559

Term of patent 14 years

U.S. Cl. D30—13
Int. Cl. D6—01; D30—02

FIGURE 1 is a perspective view of the front and top of a holder for food bowl for pets, showing my new design;

The bowl and wire mesh shown in broken lines in FIG. 1 is depicted for purposes of illustration only.

I claim:

The ornamental design for a holder for food bowl for pets, as shown and described.
